UNITED STATES PATENT OFFICE.

JAMES McMILLEN, OF RALEIGH, NORTH CAROLINA, ASSIGNOR OF ONE-HALF TO E. C. WOODWARD, OF RICHMOND, VIRGINIA.

CONCRETE FLOOR.

No. 925,941.

Specification of Letters Patent.

Patented June 22, 1909.

Application filed May 13, 1908. Serial No. 432,637.

To all whom it may concern:

Be it known that I, JAMES McMILLEN, a citizen of the United States of America, residing at Raleigh, in the county of Wake and 5 State of North Carolina, have invented new and useful Improvements in Concrete Floors, of which the following is a specification.

My invention relates to improvements in concrete floors.

10 The primary object of the invention is the provision of a floor structure of this type which includes a plurality of concrete supporting plates provided with flanges which reinforce the concrete, one flange of each 15 plate being provided with a flange extending downwardly and outwardly from the upper edge thereof to overlap one of the flanges of the next adjacent plate, said downwardly and outwardly extending flange preventing 20 the liquid in the concrete flowing downwardly between the plates during the setting of the concrete.

The invention is hereinafter fully disclosed in the accompanying drawing wherein:—

25 Figure 1 is an end elevation of a concrete floor structure made in accordance with my invention. Fig. 2 is a sectional view thereof, and Fig. 3 is a detail perspective view of a fragmentary portion of one of the supporting 30 plates.

Referring to the drawing by reference numerals, 1 designates a supporting plate which may be of any length and width and which may be constructed of any material suitable 35 for the purpose. The plate is provided with flanges 2 and 3 which extend at right angles thereto and from the same side thereof. The flange 3 is provided with a flange 4 which extends downwardly and outwardly from the 40 upper edge thereof, the flange 4 being wholly arranged outside of the plane of the plate 1. The flanges are co-extensive in length with the length of the plate 1 and formed integral therewith. 5 designates the supporting 45 beams and 7 the concrete of the floor structure.

In practice the plates 1 are secured to the supporting beams 5 by means of nails 6 or their equivalents, the plates being provided with openings which permit the passage of 60 the nails or their equivalents. The plates 1 extend transversely of the supporting beam and are so arranged that the flange 2 of one plate engages the flange 4 of the next adjacent plate and the flange 4 of one plate extends down and over the flange 2 of the next adjacent plate. After the plates have been secured in applied position, the concrete 7 is placed thereon, the concrete consisting of 65 proper proportions of sand, cement and water. The concrete sets about the flanges and is reinforced thereby, the concrete being supported by the plates 1. The flanges 4 prevent the liquid in the concrete from flowing 70 downwardly between the plates during the setting thereof.

It should be apparent from the above description, taken in connection with the accompanying drawing, that my improved floor structure is simple, durable and efficient, and that the same may be set up in a comparatively short time and at a comparatively low cost.

Having thus described the invention, what is claimed as new is:—

A floor structure comprising supporting beams, plates secured to the supporting beams and provided with flanges extending at right angles thereto and from the same side thereof, one of said flanges being provided with a flange extending downwardly and outwardly from the upper edge thereof and overlapping one of the flanges of the next adjacent plate, and concrete placed upon the plates.

In testimony whereof I affix my signature in presence of two witnesses.

JAMES McMILLEN.
